UNITED STATES PATENT OFFICE.

FREDERICK J. RUMPELTIN, OF RIDGEWOOD, NEW JERSEY.

PIPE-CLEANER.

1,176,250.

Specification of Letters Patent.

Patented Mar. 21, 1916.

Application filed January 15, 1914. Serial No. 812,179.

To all whom it may concern:

Be it known that I, FREDERICK J. RUMPELTIN, a citizen of the United States, residing at Ridgewood, New Jersey, have invented certain new and useful Improvements in Pipe-Cleaners, of which the following is a clear, full, and exact description.

This invention relates to a device the purpose of which is to clean a tobacco pipe. 10 A principal object of the invention is to produce a device for this purpose which will operate effectively to clean out the cup of the bowl and which will also operate to remove the incrustation or deposit which accumulates on the inner face of the wall of the bowl.

Further objects of the invention will appear more clearly hereinafter.

The invention consists in the general combination of parts and simplicity of details hereinatfer described, all of which contribute to produce an efficient pipe cleaner.

A preferred embodiment of my invention will be particularly described in the following specification, while the broad scope of my invention will be pointed out in the appended claims.

In the drawings, Figure 1 is a front elevation of the device indicating the manner in which it is employed in cleaning out the cup of a pipe bowl; Fig. 2 is a view similar to Fig. 1 but showing the device as in the act of cleaning the side walls of the pipe bowl; Fig. 3 is a side elevation showing the lower part of the device, the upper part being broken away; Fig. 4 is a cross section through the device taken on the line 4—4 of Fig. 1; Fig. 5 is a cross section through the device taken on the line 5—5 of Fig. 40 2; and Fig. 6 is a cross section through the handle of the device taken on the line 6—6 of Fig. 2.

Referring more particularly to the parts, I prefer to construct the cleaner in two parts 45 7 and 8, giving the device a tube-like form, that is each of the parts 7 and 8 has substantially the form of one-half of a tube which is split longitudinally. The lower extremity of each part 7 and 8 is formed into a tapered 50 semi-conical jaw 9, and these jaws have flanges or lips 10 which are normally held together in the position indicated in Fig. 1. They are preferably held in this position by means of a spring 11, which may be in 55 the form of a coil spring held in place by pivot pin 12 which pivotally connects the

two parts together. The jaws 9 when together form a substantially conical extension or shell which is adapted to be received in a pipe bowl 13. The lower extremity of the flanges or lips 10 form a rounded nose 14 which may be held against the cup 15 of the pipe bowl and rotates so as to clean the bowl at this point and dislodge any incrustation. The upper portion of the parts 60 7 and 8 form a handle 16 for the device, consisting of two semi-tubular parts or handle extensions 16^a and 16^b disposed on the side of the pivot remote from the jaws. When these parts are forced together they 65 overcome the force of the spring 11 and spread the jaws 9 apart. The sides of the jaws 9 are provided with scrapers 17 which are preferably formed by forcing the material of the jaw outwardly in such a way as 70 to form an outwardly projecting fin, and these fins preferably taper, that is they increase in width in an upward direction, so that when the jaws are opened as indicated in Fig. 2, the edges of these scrapers lie substantially parallel with each other and with the inner wall of the bowl of the pipe. With 75 the cleaner held in this position it will be evident that if it is revolved the scrapers 17 will break off the crust and clean the wall 80 of the bowl. When the scrapers are struck from the jaws 9 as indicated, they produce elongated triangular openings 18 in the wall 85 of each jaw.

In Fig. 4 the jaws are represented closed 90 together, that is with their lips 10 held together as they are normally held by the spring 11. In Fig. 5 the jaws are represented as held apart.

A pipe cleaner embodying my invention 95 evidently may be economically formed and it will evidently operate very effectively to clean the bowl of a smoker's pipe.

It is understood that the embodiment of the invention described above is only one 100 of the many embodiments or forms the invention may take, and I do not wish to be limited in the practice of my invention or in my claims to the particular embodiment set forth.

What I claim is:

1. A pipe cleaner consisting of two members having a pivotal connection upon each other, said members having jaws forming parts of a substantially conical shell adapted to be received within the pipe bowl, said conical shell having an integral flange pro-

jecting outwardly at the extremity thereof adapted to engage the bottom of the bowl when said jaws are closed together, said jaws having scrapers struck integrally from the conical walls thereof projecting outwardly and extending longitudinally along the conical faces thereof, said scrapers operating to engage the inner face of the pipe bowl when said jaws are held separated, 10 said members having handles adapted to be grasped to move said jaws with relation to each other.

2. A pipe cleaner consisting of two members having a pivotal connection upon each other, said members having jaws forming parts of a conical shell to be received within the pipe bowl, said shell having an integral projecting flange at the extremity thereof to engage the bottom of the bowl when said 15 jaws are closed together, said jaws having scrapers in the form of fins struck integrally outwardly from the walls thereof projecting and extending longitudinally along the conical faces thereof, said scrapers operating to engage the inner face of the pipe bowl when said jaws are held separated, said members having handles adapted to be grasped to move said jaws with relation to each other, and a spring tending to hold said jaws in 20 an extreme position.

3. A pipe cleaner consisting of two substantially semi-tubular members oppositely disposed to form a handle, said members being pivotally connected together and having jaws below the pivotal connection therebetween forming a tapered extension adapted to be received in a pipe bowl, said jaws having longitudinally disposed scrapers 35

struck from the material thereof adapted to engage the wall of the pipe bowl to clean 40 the same when said cleaner is rotated.

4. A pipe cleaner consisting of two members having a pivotal connection upon each other, said members having oppositely disposed extensions forming a handle and having oppositely disposed conical jaws, said jaws having integral flanges at the meeting edges thereof forming a rounded scraper at the ends of said jaws for scraping the bottom of the bowl of the pipe, said jaws having integral laterally projecting scrapers in the form of fins disposed on opposite sides of the pivotal connection and operating to swing outwardly when said handles are pressed to engage the inner face of the 50 wall of the pipe bowl, and means tending to hold said jaws close together.

5. A pipe cleaner consisting substantially of two jaws, each jaw consisting of a semi-conical shell, said jaws having integral outwardly projecting flanges meeting flatly together when said jaws are closed, a pivot connecting said jaws, said jaws having handle extensions integral therewith on the side of said pivot remote from said jaws, said jaws having integral scrapers in the form of fins struck outwardly and extending longitudinally of the said jaws, and a spring engaging said handle extensions normally holding said jaws together.

Signed at New York, N. Y., this 14th day of January, 1914.

FREDERICK J. RUMPELTIN.
